UNITED STATES PATENT OFFICE.

ERNEST S. JAROS, OF COLUMBUS, OHIO, ASSIGNOR TO THE UNITED DEMONSTRATING MACHINE COMPANY, OF COLUMBUS, OHIO, A CORPORATION OF OHIO.

ADVERTISING NOVELTY.

1,239,013.

Specification of Letters Patent. Patented Sept. 4, 1917.

Application filed June 10, 1912. Serial No. 702,816.

To all whom it may concern:

Be it known that I, ERNEST S. JAROS, a citizen of the United States, residing at Columbus, in the county of Franklin and State of Ohio, have invented certain new and useful Improvements in Advertising Novelties, of which the following is a specification.

My invention relates to an advertising novelty and consists in the provision of apparatus for symbolically indicating the superiority of hosiery as regards its capability for wear at vulnerable points. More specifically, my invention aims to provide a means for fancifully representing to the casual observer that certain hosiery, the merits of which are under consideration, is capable of a comparatively great wear at the heel, toe and knee. It is further designed to not only subject these particular points of the stocking to wear, but to subject them to wear practically identical in nature to the wear to which these points are normally subjected while on the foot of the wearer.

Furthermore, my invention contemplates the provision of supplemental indicating means which are intermittently and automatically effective to attract or direct attention to the wearing action. This supplemental indicating means is desirably effective at the same time each action occurs and has been shown in the present instance as being of a luminous nature.

My invention may vary as to form and embodiment, but the preferred apparatus utilized is shown in the accompanying drawings, in which similar characters of reference designate corresponding parts, and in which:

Figure 1 is a front elevation of my improvement,

Fig. 2 is a vertical longitudinal section of my apparatus,

Fig. 3 is a section taken on line 3—3 of Fig. 2,

Fig. 4 is a detail in plan of a double cam structure utilized by me for a purpose to be hereinafter described,

Fig. 5 is a side elevation of the structure shown in Fig. 4,

Fig. 6 is an end elevation of this structure shown in Figs. 4 and 5,

Fig. 7 is a side elevation in detail of a means for operating a register which I desirably attach to my device,

Fig. 8 is a section taken on line 8—8 of Fig. 7,

Fig. 9 is a detail view of a slidable arrow plate structure which is calculated to attract attention of the observer to the rubbing of the knee, and,

Fig. 10 is a section taken on line 10—10 of Fig. 9.

In the drawings, my invention is shown as comprising what may be termed a show-case having vertical standards 1 and cross pieces 2 and 3, which support the display portion proper of box-like formation and designated 4. This box-like formation in turn is divided into compartments 5 and 6 and in the compartment 5 which has a transparent front, there is disposed an artificial limb 7 desirably inclosed in a stocking and capable of movement in an approximately elliptical path of travel under the ultimate control of a motor 8 driving a worm gear 9 by means of a worm 10, such worm gear 9 being mounted upon a shaft 11 carrying a gear 12 which in turn meshes with a gear wheel 13 upon a shaft 14. This shaft 14 is primarily equipped with a double cam structure (shown best in Figs. 4, 5 and 6) as comprising an inner cam 15 and an outer cam 16 constructed for coöperation with an arm 17 pivotally supported at one end from a link 18, in turn pivoted to a pendent 19 upon the upper wall of the display portion 4. The arm 17 is peculiar in its formation, in that it carries a heel member 20 carrying upon its upper end a pierced lug 21 to which is attached a tension spring 22 permanently secured at its opposite end. This arm 17 extends in coöperative relation with the double cam structure and when in such coöperative relation, the arm is so disposed as to be forced rearwardly by the inner cam 15 operating upon the heel 20 and then upwardly by the outer cam 16 operating upon the arm 17. The forward movement of the arm 17 is automatically effected by the spring 22.

which has been previously tensioned. It will be apparent from the structure and operation thus far described, that the limb 7, assuming it to be in normal position in Fig. 2, is caused to move rearwardly, then upwardly under the successive influence of the double cam elements and is finally returned to normal position by the spring 22 simultaneously with the lowering of the lifting cam element.

It being understood that the limb 7 assumes this same general path of travel at all times, attention is directed to the main rubbing or wearing surface 23 and the auxiliary rubbing or wearing surfaces 24 and 25. This rubbing surface 23 is desirably a portion of the floor 26 of the casing 5, whereas the auxiliary rubbing or wearing elements 24 and 25 are desirably in the form of blocks supported by pins 27 and 28 and yieldable against the springs 29. These rubbing elements 24 and 25 are accurately disposed to receive the rubbing impact of the toe and heel respectively of the limb and to receive such rubbing impact with a yielding resistance. Disposed in proximity to these wearing or rubbing blocks 24 and 25, I desirably provide signal lights 30 and 31 in the form of globes fed by wires 32 and 33 respectively. Also, I desirably provide an indicating device beneath the surface 23 and this indicating device comprises a light 34 in the form of a globe fed by electric wires 35. The faces of the inclosures for the lights 30 and 31 are preferably in the form of plates 36 and 37 having cut-out arrows pointing toward the point of contact of the toe and heel respectively with the wearing or rubbing blocks 24 and 25. The light 34 has an inclosure with a face plate 38 cut away as at 39 and having a slideable arrow plate 40 disposed in the rear thereof and in turn carrying a glass plate 41. This slide plate is preferably provided with a flange 42 and is reciprocable under the control of a reach rod 43 connected by a link 44 to the arm 17. Because of this connection, the rearward movement of the arm 17 which serves to move the knee into rubbing contact with the surface 23, likewise serves to move the slide plate rearwardly through the medium of the link 44 and reach rod 43 and in consequence thereof the arrow moves in substantial coincidence with the knee of the limb 7.

My invention is preferably equipped with a registering device as shown at 45 which is caused to register by the lifting of a lever arm 46 and the lifting of this lever arm is desirably effected by a cam slide 47 shown best in Figs. 7 and 8 and comprising a block 48 and a plate 49 secured thereto. This block 48 is bored as at 50 for slidably mounting upon a guide rod 51. The block

is likewise connected to a reach rod 52 which is in turn connected to a lever 53 pivotally supported as at 54 from the base of the display portion 4. This lever 53 is normally forced rearwardly by a pin 55 upon the gear wheel 13 which moves into contact therewith once in every rotation of the said gear wheel 13 and its shaft 14. The lever is returned by a spring 56 being stopped on its return by a cushioned frame 57. By reference to Fig. 2, it will be seen that rearward movement of the lever 53 operates through the medium of the link 52 and the plate 49 of the block 48 to raise the arm 46 and operate the register 45. This register 45 is supplemented by a hood 58 having a light 59 therein in the form of an electric globe, fed by wires 60.

The motor may be fed through the main lines 61 and 62 under the control of a button switch 63 and it is desirable to provide a fuse-box 64, it being understood that the lines 61 and 62 may be led into the motor in the customary manner. These lines 61 and 62 are desirably provided with a shunt 65 under the control of a button switch 66 and one line from each lamp leads to a contact bar 67 within the shunt, while the other wires of the lamps are connected to contact fingers 68. These fingers 68 are of the form common to switches of this type and cooperate with a rotating contact element 69 upon the shaft 14. There is likewise provided a finger 70 which is electrically connected to the switch 66. This completes the various circuits and it will be understood that the operation of the switch is deemed to successively light the lamps at predetermined instants. For instance, when the toe of the limb 7 is rubbing upon the block 24, the circuit is closed through the lamp 30 causing a lighting of the same and a consequent attraction of the attention thereto. When the heel is rubbing upon the rubbing block 25, the circuit is closed through the lamp 31 which likewise results in the lighting of that lamp. When the knee of the limb is rubbing upon the surface 23, the circuit is closed through the lamp 34 and this lamp is lighted. The lighting of the lamp 59 of the register desirably takes place shortly after the close of the rubbing operation upon the knee of the limb, although it will be understood that the time of these operations may be varied at will.

In claiming my invention, I have specified the knee portion of the artificial clothed member as being subjected to a wearing action. As the knee portion affected in actual wear, is that portion represented by the underside of the leg form, or, in other words, that portion covering the knee cap, I have provided a machine for acting upon this portion and this interpretation is to

be given wherever the knee is claimed as being subjected to a wearing action.

It will be apparent that I have provided an advertising novelty which is feasible and attractive and which by means of the plurality of successive operations, enables me to successfully and symbolically indicate to the observer that certain portions of a stocking, namely, those portions most generally 10 subject to wear, are peculiarly strong and durable.

What I claim is:

1. An advertising novelty comprising an artificial clothed member, a resiliently mounted wearing element, and means for bringing said member into percussive engagement with said element against the tension of its resilient mounting.

2. An advertising novelty comprising an artificial clothed member, a resiliently mounted wearing element, means for bringing said member into percussive engagement with said element against the tension of its resilient mounting, and positively controlled 25 means for subsequently causing a relative movement between said member and said element.

3. An advertising novelty comprising an artificial clothed limb, means for imparting a series of wearing actions to the heel and toe of said limb, a knee abrading element, and means for repeatedly bringing the knee portion of said limb and element into engagement and subsequently causing a relative movement between them while they are 35 in such engagement.

4. An advertising novelty comprising an artificial clothed limb, heel, toe and knee abrading elements, means for moving the 40 heel, toe and knee portions of said limb into percussive contact with their respective abrading elements, and means for moving the knee portion over the surface of the knee abrading element while in contact therewith 45 after the percussive action.

5. An advertising novelty comprising an artificial clothed limb, an abrading element, and means for subjecting the knee portion of said limb to a percussive action and also 50 causing a relative movement between said element and the knee portion of said limb while they are in engagement.

6. An advertising novelty comprising an artificial clothed limb, an abrading element, and means for bringing the knee portion of 55 said limb and said element into engagement and subsequently causing a relative movement between them while they are in such engagement.

60 7. An advertising novelty comprising an artificial clothed limb, an abrading element, and means for moving the knee portion of said limb into percussive contact with said element and subsequently bodily moving

said limb while the knee portion is still in 65 engagement with said abrading element to cause a rubbing action to the knee portion.

8. An advertising novelty comprising an artificial clothed limb, a casing for said limb, means for moving said limb into contact 70 with said casing, and means for causing relative movement between said limb and said casing when in contact.

9. An advertising novelty comprising an artificial clothed limb, a casing for said 75 limb, an element resiliently mounted in said casing, and means for bringing said limb and said element into percussive contact.

10. An advertising novelty comprising an artificial clothed limb, a casing for said limb, 80 elements resiliently mounted in said casing, means for bringing the heel and toe of said limb into percussive contact therewith, and means for imparting a rubbing frictional action to the knee of said limb. 85

11. An advertising novelty comprising an artificial clothed member, means for imparting a series of moving wearing actions to said member, supplemental luminous indicating means for directing attention when 90 such action occurs, and means for moving said luminous indication synchronously with the wearing action.

12. An advertising novelty comprising means for supporting the article on display, 95 means for imparting a series of wearing actions to said member, supplemental indicating means, and means for rendering said last means intermittently and automatically effective with the wearing actions for directing 100 attention to the affected parts when such action occurs.

13. An advertising novelty comprising an artificial clothed member, means for imparting a series of wearing actions to said member, and supplemental indicating means intermittently and automatically effective with the wearing actions for directing attention 105 when such action occurs.

14. An advertising novelty comprising an 110 artificial clothed limb, means for imparting a series of percussive actions to said limb, means for imparting a series of rubbing frictional actions to said limb, supplemental luminous indicating means, means for rendering said luminous means operable for directing attention to said limb when such percussive actions occur, a movable luminous indicator, and means for rendering said indicator operable for directing attention 115 when such frictional action occurs. 120

15. An advertising novelty comprising an artificial clothed member, means for imparting a series of wearing actions to said member, a supplemental luminous indicating 125 means comprising a pointer, and means for intermittently and automatically rendering said luminous means operable for directing

attention to said member when such wearing actions occur.

16. An advertising novelty comprising an artificial clothed member, means for imparting a series of wearing actions to said member, supplemental luminous indicating means comprising a pointer, and means for rendering said luminous means operable for

directing attention to the affected parts when such action occurs. 10

In testimony whereof I affix my signature in presence of two witnesses.

ERNEST S. JAROS.
